UNITED STATES PATENT OFFICE.

SILAS G. RICHARDS, OF ROCKFORD, ILLINOIS, ASSIGNOR OF ONE-HALF TO ARTHUR B. McCALL, OF SPRINGFIELD, ILLINOIS.

SCOOTER SLED.

Application filed February 5, 1927. Serial No. 166,255.

My invention relates to sleds and more particularly to narrow sleds of an improved construction especially adapted for use by children.

5 An object of my invention is to provide a sled of the above indicated character which has skate runners and is adapted to be operated on ice with great facility.

Another object of my invention is to provide 10 a sled as above indicated which is easy to operate, and having the tongue so located and mounted that its operation will not split the top board of the sled.

15 Heretofore many types of sleds have been made but none of them have been adapted to be used on ice, and having sharpened 65 skate runners such as incorporated in my invention. My invention is especially a great improvement over Patent No. 1,577,078, issued to Richards, dated March 16, 1926, in that the tongue of the sled in said Richards' construction was so located that the top boards of the sleds were constantly being split thereby, and rendering the same 70 useless. By my present invention I obviate this difficulty by providing a new and improved type of mounting for the tongue.

20 My invention will be best understood by reference to the drawings forming a part 75 of this specification and in which:

Figure 1 is a top plan view of a sled incorporating my invention.

Figure 2 is a side view of the same.

Figure 3 is a bottom view of the same.

35 Figure 4 is a front view of the sled taken on line 4-4 of Figure 2 and,

Figure 5 is a cross-sectional view taken on the line 5-5 of Figure 2.

40 In the drawings and for the purpose of illustration I have shown the preferred embodiment of my invention, and in which numeral 6 represents a sled top provided with sharpened steel skate runners 7, diverging very slightly toward the front as shown. The ends of the runners are curved upwardly at 8 and 9 and secured to the top of the sled at the front and rear by suitable bolts 10 and 11 respectively. The extreme 45 front ends of the skate runners are bent upwardly again beyond the point where they are secured by bolts 10, and they pass upward through slots 12 in the top of the sled.

Between these upward projecting ends 13 is pivotally secured a bar portion of a tongue 14, by a suitable bolt 15, well above the plane of the top 6, which allows the tongue to be turned forward for drawing the sled or turned backward to aid in steering by the person riding.

This particular construction obviates the 60 splitting of the top board 6 when the tongue is twisted sidewise for the purpose of steering the sled.

Across the top of the sled are secured by 65 bolts 18 and 19 two cross-bars or re-enforcing members 16 and 17, which may be used as foot rests by the occupant. Near the end 70 of the tongue 14 are provided handles 20 in the form of a cross-bar tightly pressed through a hole in the tongue 14 as shown in Figure 2.

75 While I have described my invention in its preferred form it will be obvious that many variations may be made therein without departing from the spirit of the invention; I do not, therefore, wish to be limited to the precise details as described but desire to avail myself of such variations and modifications as come within the scope of the appended claims.

80 I claim as my invention:

1. A sled comprising a top having two slots in the forward portion thereof; skate runners under said top and having the extreme front ends of said runners extending 85 upwardly through said slots; a tongue having one end pivotally secured between said extensions, and having a handle on the other end thereof; and a plurality of foot rests provided on the sled top.

90 2. A sled comprising a top having slots in the forward end, and means extending upwardly therethrough to which a tongue bar is pivotally secured well above the plane of said top, whereby the splitting of said top is prevented; sharpened steel skate runners under said top and having the ends curved upwardly and secured to said top; foot rest bars on the top and a handle for aiding in steering the sled.

100 In testimony whereof I have signed my name to this specification.

SILAS G. RICHARDS.
